COIN DEVICE

Otto A. Hokanson, Snyder, N. Y., assignor to The
Rudolph Wurlitzer Company, North Tonawanda, N. Y., a corporation of Ohio

Application August 12, 1942, Serial No. 454,555

16 Claims. (Cl. 194—99)

This invention relates to certain new and useful improvements in coin devices of the type designed to reject spurious coins or slugs and thereby prevent the operation of the apparatus with which devices of this character are used.

One of its objects is to provide a coin device of this character which has been designed for use with five, ten and twenty-five cent coins to effectively separate and direct non-acceptable coins through paths different from those taken by acceptable coins.

Another object of the invention is to provide simple and reliable means for scavenging the device of non-acceptable coins which have been arrested by testing devices disposed in their path of travel.

A still further object is to provide a coin device of this character which is simple and compact in construction, whose parts are adjustable to insure separation of spurious coins from genuine coins, which can be readily assembled as well as be readily opened up for inspection for repair or adjustment, and which is reliable and efficient in operation.

Other features of the invention reside in the construction and arrangement of parts herein-after described and particularly pointed out in the appended claims.

In the accompanying drawings:

Figure 1 is a front elevation of the coin device embodying my invention. Figure 2 is a rear view thereof, partly in section. Figure 3 is a front view of the base plate and associated parts with the gate and slug receptacle removed. Figures 4 and 5 are enlarged fragmentary horizontal sections taken substantially in the planes of the correspondingly numbered lines in Figures 1 and 2, respectively. Figures 6 and 7 are vertical sections taken substantially on the correspondingly numbered lines in Figure 3. Figure 8 is a fragmentary vertical section taken on line 8—8, Figure 1. Figure 9 is a fragmentary horizontal section taken on line 9—9, Figure 1. Figure 10 is a fragmentary, rear perspective view, partly in section, of the base plate. Figures 11 and 12 are perspective views of the gate and the knockout plate, respectively. Figure 13 is a perspective view, partly in section, of the slug receptacle. Figure 14 is a fragmentary perspective view of the lower portion of the knockout plate and associated parts.

Similar characters of reference indicate corresponding parts throughout the several views.

In its general organization, this device has a common coin-receiving opening for receiving five,

ten and twenty-five cent coins, supplementary passages into which the twenty-five, and five, and ten cent coins, respectively, are directed for testing, means for testing the coins as they traverse such passages by gravity, discharge passages or chutes into which the tested coins are directed and separated in different paths depending upon whether they are acceptable or non-acceptable, a scavenging mechanism for ejecting from the device any coins which have been arrested in their travel through the same by failure of meeting the requirements or characteristics of genuine or acceptable coins, and a receptacle or cup into which scavenged or other non-acceptable coins are adapted to be directed. In traveling through the device the coins are tested as to size, weight, whether magnetic or non-magnetic, as well as to their electrical conductivity and hardness.

In the preferred embodiment of the invention shown in the drawings, the same comprises an upright base plate 10 having forwardly-facing flanges 11 projecting from its opposite side edges and over the front face of which the coins travel by gravity for testing and separation to acceptance or reject chutes; a side or horizontally-swinging gate 12 extending over the front face of the upper half portion of the base plate and normally spaced therefrom a sufficient distance to provide a coin passage between such parts; a knockout plate 13 hinged to the rear side of the base plate to swing toward and from the same and having a plurality of forwardly-facing lugs 14 at different predetermined locations thereon for projection through corresponding openings 15 in the base plate to dislodge any coins which have been arrested in their travel through the chute from testing or otherwise; and a slug box or receptacle 16 disposed over the lower half of the front face of the base plate, also in such spaced relation thereto to provide a continuation of the coin passage or chute and down which the tested coins roll for separation into the acceptance or reject chutes. The acceptance discharge chute for twenty-five cent coins is indicated at 17 and is located at the rear side of and in parallel relation with the base plate 10, being shaped substantially as shown in Figure 10 of the drawings, and directing such coins to a point where they will operate the coin mechanism of the phonograph or other apparatus to which this coin device is connected. At its upper or inlet end this twenty-five cent coin acceptance chute is in registering communication with an opening 18 formed in the base plate above the receptacle 16 and having a deflector 19 adjoining the same for directing

a tested, acceptable twenty-five cent coin laterally from the base plate chute into its acceptance chute 17. That portion of the gate 12 overlying this opening and deflector is forwardly offset or displaced sufficiently to permit the required angular displacement of the coin as it enters the opening 18. Acceptable five and ten cent coins, after test, find their way to separate, companion acceptance discharge chutes 20 and 21, respectively, located side by side at the lower front, left hand side of the base plate and between it and the opposing rear face of the slug receptacle 16. Five cent slugs and certain other denominations here considered may be directed, after test, to a common reject discharge chute 22 located at the right hand side of the base plate between it and the slug receptacle. In most cases, however, rejected coins would be deflected into the slug receptacle through an opening 23 and deflecting edge 24 formed in the rear wall thereof, as shown in Figure 13.

The slug receptacle 16 is open at its upper end over the full width thereof to receive any coins which have been arrested in the upper testing portion of the coin chute above the plane of the receptacle and which have been subsequently released by the knockout plate 13 or otherwise scavenged in a manner as will hereinafter appear. To facilitate the gravity discharge of the rejected coins or slugs from this receptacle, it has a sloping bottom wall 25 and a discharge opening 26 at the right hand side thereof adjoining the common reject chute 22. This receptacle is detachably secured to the base plate 10 by tongues 27 projecting from one side of the receptacle and engaging companion openings 28 in the adjoining plate-flange 11, while a spring-urged latching lever 29 is applied to the opposite side of the receptacle and has a coupling tongue 30 thereon for engagement with a companion opening 31 in the opposing base-flange 11.

The upper or testing portion of the coin passage formed between the base plate 10 and the gate 12 is provided with a coin-receiving opening or passage 32 through which five, ten and twenty-five cent coins are deposited into the device and then allowed to roll edgewise in the plane of the base plate to be tested and separated. Upper and lower inclined ledges or tracks 33, 34 separate the path of twenty-five cent coins from those of five and ten cent coins, the twenty-five cent coins or slugs being guided along the upper track 33 and the other denomination coins or slugs being guided on the lower track 34. Pivoted at 35 to the rear side of the base plate and below the mouth of the coin-receiving opening 32 is a vertically-swinging, counter-balanced cradle 36 having forwardly-facing lugs or abutments 37 at opposite sides of its pivot which extend through the adjoining openings 15 in the base plate and which are so spaced as to permit five and ten cent coins to pass downwardly there-between onto the lower track 34, but which intercept a twenty-five cent coin, the weight of the latter causing the cradle to rock in a clockwise direction and shifting the coin to a position where it will roll free of the cradle onto the upper track 33. In traveling along the respective inclined passages defined by the tracks 33, 34, the coins enter a zone of magnetic flux created by electromagnets 38 applied to the gate 12 and opposing keepers 39 applied to the knockout plate 13. Depending upon the metallic content of the coins, their speed of travel is retarded or not as they pass through the magnetic flux and they leave the tracks 33, 34

or 34 in various trajectory paths as determined by their resulting velocity.

Means are disposed in these various paths for effecting the separation of the acceptable coins from the spurious coins or slugs and thence directing such coins, respectively, to their companion acceptance or reject discharge chutes. The separating means associated with the trajectory path of the twenty-five cent coins or slugs preferably consist of deflectors or impact members 40, 41 which are disposed, as shown in Figure 3 adjacent the opposite ends of the acceptance opening 18 leading to the twenty-five cent coin chute 17, so that a genuine twenty-five cent coin, after leaving the inclined track 33 will fall in a trajectory to pass between these deflectors and into the acceptance chute. A twenty-five cent slug, which is not affected by the magnetic flux and therefore leaves the track at a high velocity, strikes the upper deflector 40 and is rebounded therefrom clear of the acceptance chute opening 18 and takes a path of travel where it is discharged into the slug receptacle 16. A twenty-five cent slug, which is materially retarded by the magnetic flux and therefore drops sharply downwardly from the end of the track 33, encounters the lower deflector 41 and is likewise directed to the reject chute. By preference this deflector 41 is in the form of a yieldable element or wire which, when encountered by a coin, flexes downwardly and cushions the impact. A third deflector 42 is disposed below the companion deflectors 40, 41 and in the path of the descending travel of the deflected twenty-five cent slugs to direct them laterally toward the reject chute 22, or to deflect them toward the opening 23 and thence into the slug receptacle 16. By preference, this deflector 42 is pivoted at 42a to its supporting bracket, as shown in Figure 2, and is counterweighted to normally assume the position shown but is free to be displaced in one direction when engaged by a ten cent coin to cushion the impact, but is held against swinging in the opposite direction to deflect slugs into the reject chute or receptacle. To assist in such disposal of the slugs into the receptacle, its front wall is depressed inwardly adjacent the area of the opening 23 to provide an abutting portion 43 against which the slugs are adapted to contact and by which they are brought into a properly aligned position to freely drop into the receptacle. A fourth deflector 44 is disposed to the left of the deflector 42 and spaced therefrom sufficiently to provide for the passage of any of the coins therebetween. Like the companion deflectors, this one serves to separate the spurious coins by deflecting them in paths leading to the reject chute 22 or the slug receptacle 16.

The deflectors 40, 41, 42 and 44 are mounted on the rear side of the base plate 10 and their coin-engaging portions extend through the companion openings 15 provided in such plate. These deflectors are adjustable to readily position them as desired and for this purpose are provided with slots 45 for receiving the fastening bolts 46.

Disposed at the lower right side of the coin passage through which the rejected coins descend to the discharge chute 22 is an anvil 47 which is secured to the front face of the base plate 10 below and to the right of the deflector 42. Genuine five cent coins introduced into the device engage and roll down the lower inclined track 34 and then follow a trajectory which brings them into contact with this anvil, from which they are rebounded in an arcuate path toward the

left hand side of the base plate from which they descend through the acceptance chute 20.

Between the latter and the anvil 47 and below the deflector 42 and the normal rebound path of a genuine five cent coin is a vertically-swinging, counterbalanced cradle 48 pivoted at 49 to a bracket 50 adjustably secured to the rear side of the base plate and having forwardly-facing lugs or coin abutments 51 at opposite sides of its pivot which extend into the coin passage through adjoining openings 15 in the base plate. These cradle-lugs are spaced apart sufficiently to permit a ten cent coin descending through the coin passage to freely pass therebetween to the companion acceptance chute 21 which is in vertical alinement with such lug-creating coin path. However, five and twenty-five cent coins which may descend toward this cradle are intercepted thereby, the weight of such coins tilting the cradle and dumping them into the reject discharge chute 22.

Above the rebound path of a genuine five cent coin and between the deflector 42 and the left hand side of the base plate 10 are superposed spacing studs or pins 52 which not only maintain the base plate and slug receptacle 16 in uniform spaced relation to provide the coin passage, but are so positioned as to prevent other coins reaching the acceptance chute 20 and to deflect them in directions away from such chute. Similar studs 52^a are located along the lower edge of the base plate to separate the coin chutes 20, 21 and 22.

In considering the travel of ten cent coins and slugs through the device, a legitimate ten cent piece, after leaving the inclined track 34, takes a trajectory between the deflectors 41, 44 and strikes and displaces the pivoted deflector 42 at a point to the right of its center of gravity and then descends between the lugs 51 of the lower cradle 48 into the acceptance chute 21. A slow moving ten cent slug, or one which is retarded by the magnetic flux, encounters the deflector 44 and drops onto the deflector 42 at a point to the left of its center of gravity and from which point it descends into the slug receptacle 16. A fast-moving slug, or one unaffected by the magnetic flux, takes a trajectory where it strikes the right side of deflector 42 and is then rebounded therefrom and deflected either through the opening 23 into the slug receptacle 16 or into the reject chute 22.

Considering now the travel of five cent coins and slugs through the device, a legitimate five cent piece takes a trajectory which clears the deflectors 41, 42 and 44 and strikes the anvil 47 from which it is rebounded over the cradle 48 into the acceptance chute 20. A slow-moving five cent slug, or one retarded by the magnetic flux, may strike against the deflectors 44 and 42 and be deflected laterally from the latter into the slug receptacle 16 or it may be deflected to the right by the deflector 42 and descend straight downwardly between the anvil 47 and the opposing cradle-lug 51 into the reject chute 22; or it may be deflected to the left of the deflector 42 against one or the other of the pins 52 and then descend onto the cradle 48 to be rocked thereby toward and into the reject chute. A fast-moving five cent slug, or one unaffected by the magnetic flux, passes over the deflector 44 and drops onto the deflector 42, from which it is deflected into the slug receptacle or the reject chute 22; or it may be trajectory from the deflector 42 and then

onto the cradle 48 from which it is dumped into the reject chute.

Means are provided in the upright intake portion of the coin passage and in a plane below the twenty-five cent coin track 33 for intercepting or separating light undersize coins as well as perforated slugs or washers introduced into the coin-receiving opening 32 and deflecting them away from the coin track 34 and into the slug receptacle 16. For intercepting light-weight slugs made of cardboard, Bakelite and the like, I provide vertically-swinging, counterbalanced levers 53, 53^a pivoted at 54 to the rear side of the base plate 10 to swing in the plane thereof and terminating at their free ends in forwardly-bent lugs 55 and 55^a, respectively, the former of which extends through the companion opening 15 formed in such plate into the path of the introduced coins, while the latter is disposed in the path of and adapted to be engaged by the lever 53 when the same is displaced by a five cent coin. Five and ten cent coins having sufficient weight displace these levers to permit them to pass on through the coin passage, while light-weight coins do not disturb the levers and they are accordingly blocked against descending in the chute until scavenged in a manner to be hereinafter described. The lever-lug 55 is disposed to intercept light-weight ten cent coins, while a light-weight five cent coin may displace the lever 53 a short distance, say, until it encounters the lug 55^a, when the combined counterweight of these levers will then come into play and prevent the escapement of the coin and it is blocked in its descent. A counterweighted, pendulum-like member 56 is pivoted at 57 to the rear side of the base plate and terminates at its lower end in a hook-like element 58 which extends through the companion opening 15 in such plate and is normally urged transversely against the rear face of the overlying gate 12 and in the path of the introduced coins. This pendulum is laterally displaced by those coins descending past the lever 53 so as not to obstruct the free descent of normal-sized coins. However, in the case of washer-like slugs, these are penetrated by the hooked end 58 of the pendulum and held thereby until scavenged. To effect the rejection and diversion of undersized coins, the gate 12 is provided with a discharge opening 59 which is disposed opposite the lower end of the pendulum 56 and for such size and shape to prevent passage therethrough of coins simulating a ten cent piece in size. Arranged over this discharge opening is a shield 60 which is open at its lower end and through which undersize coins, displaced by the pendulum through said opening, are discharged and thence dropped by gravity into the slug receptacle 16, being deflected therein by the upper inclined portion 61 of such receptacle.

The gate 12 and knockout plate 13 are hinged on a common upright pintle 62 mounted in lugs 63 on the base plate 10 and a spring 64 serves to constantly urge said gate to its normally closed position in spaced overlying relation to the base plate. A second spring 65 coiled about the pintle and having its ends in bearing engagement with the gate and the knockout plate serves to constantly urge such parts toward each other, so that when the gate is opened for scavenging purposes, for example, the knockout plate follows in a like direction with it toward the base plate, the gate having a bolt or like element 66 projecting rearwardly therefrom through an opening in the base plate and abutting the opposing free end of

the knockout plate. The magnets 38 and keepers 39 also function to move the gate and the knockout plate toward each other, while the bolt 66 enables the space between the magnets and keepers to be accurately adjusted. In the normally closed position of the gate, the knockout plate assumes a position somewhat rearwardly inclined to the plane of the base plate, wherein its lugs 14 are retracted from and clear of the coin passage. When the gate is opened, the knockout plate is automatically moved in a direction to project its lugs 14 through the aligned openings 15 in the base plate and engage any coins which may have become trapped or stuck in the coin passage and displace them from their trapped positions to enable them to drop by gravity into the slug receptacle 16. For the purpose of freeing any coins which may have been dropped in the lower cradle 48 and over which area of the coin passage the slug receptacle extends, the rear wall of the latter is provided with a transversely displaceable trap door 67 normally closing a coin-escapement opening 68 formed therein and adapted to be opened when the gate 12 and the knockout plate 13 are moved to a scavenging position and at the same time dislodge the arrested coin and permit it to drop by gravity into the bottom of the slug receptacle. This trap door is hingedly suspended from a pintle 69 mounted on a bracket 70 applied to the slug receptacle and a spring 71 engages the door to yieldingly retain it in its pendant, closed position.

The means for opening the trap door 67 and dislodging a coin trapped in the vicinity of the lower cradle 48 is associated with the lower portion of the knockout plate 13 which has a scavenging lug 14 thereon for abutting against the lodged coin and pushing it through the trap door opening 68 into the slug receptacle 16. A lever 67^a is pivoted at 13^a to the base plate 10 to swing jointly with the knockout plate, being coupled thereto by tie-lugs 67^b, and is provided at its free end with a lug 14^a which, when such plate is moved to a scavenging position, abuts the trap door and opens it. It will be noted that the respective pivots of the knockout plate and lever 67^a and the lugs 14 and 14^a are so disposed that, during the swinging of the plate to its scavenging position, the lug 14^a functions first to open the trap door and thereafter the lug 14 abuts the coin and projects it through the opening 68 into the slug receptacle.

For the purpose of scavenging any coins attracted to and arrested by the magnets 38, I provide a sweep arm 72 which is pivoted at 73 to the rear side of the gate 12 adjacent its hinged end and which is adapted to be swung across the coin passage between the magnets and their keepers 39 to dislodge the coins therefrom for discharge into the reject chute 22 or slug receptacle 16. A spring 74 is provided for normally urging this sweep arm to its retracted position clear of the coin passage. An actuating lever 75 pivoted at 76 to the upper end of the base plate 10 and having a roller 77 at its free end for engagement with the sweep arm 72 is adapted to project the latter to its scavenging position. This lever has a finger tab 78 projecting rearwardly therefrom and a spring 79 serves to normally urge it to its retracted, inoperative position.

The actuating lever 75 also serves, when depressed to push the sweep arm 72 downwardly, to open the gate 12 as well as to allow the spring 65 and magnets 38 to swing the knockout plate 13 forwardly with the gate to eject any coins

which have been arrested along the coin path. For this purpose, this lever has a second roller 80 on its front side which is adapted to engage a cam face 81 on the gate to swing the latter open when said lever is depressed.

For the purpose of directing any coins swept from the magnets by the arm 72 into the receptacle 16, I provide the knockout plate 13 with downwardly-sloping lugs 82 which extend through corresponding openings 15 in the base plate 10 when the knockout plate is swung forwardly to its scavenging position and bridge the coin passage to deflect the descending, swept coins into such receptacle.

By preference, the sloping rebound face of the anvil 47 is of crenelated form to provide a multiplicity of spaced impact surfaces of narrow width which prevent dust and dirt lodging thereon and interfering with the rebound action of the coins.

I claim as my invention:

1. A coin device of the character described, comprising means defining a coin passage having a common coin-receiving opening at its upper end for the introduction of coins of different denominations and terminating at its lower end in separate acceptance discharge chutes for the passage of certain denominational coins and a common discharge chute for non-acceptable coins of the different denominations, said means having a separate acceptance discharge chute at the rear side of said coin passage and communicating at its upper end with the latter for receiving legitimate coins of another denomination, and means in said coin passage between its coin-receiving opening and said discharge chutes, respectively, for testing the introduced coins and separating and directing them as a result of the tests to the companion acceptance chutes or to the common non-acceptance chute.

2. A coin device of the character described, comprising means defining a coin passage having a common coin-receiving opening at its upper end for the introduction of five, ten and twenty-five cent coins and separate discharge chutes for the passage of such acceptable coins and a common reject chute for the non-acceptable coins, coin-testing means in said passage for deflecting and directing the introduced coins to their respective acceptance or non-acceptance discharge chutes, and superposed runways in the coin passage between the coin receiving opening and said testing means for guiding twenty-five cent coins to a given zone of the testing means and the five and ten-cent coins to another zone of the testing means, said coin-testing means including a pair of spaced deflector elements disposed at a predetermined trajectory distance from the end of the 25¢ runway and a triangular group of spaced deflector elements disposed below the 5¢ and 10¢ runway and located at predetermined trajectory distances therefrom, whereby acceptable 25¢ coins pass between said pair of deflector elements and the acceptable 5¢ and 10¢ coins pass between the deflector elements of the triangular group.

3. A coin device of the character described, comprising means defining a coin passage having a common coin-receiving opening at its upper end for the introduction of five, ten and twenty-five cent coins and separate discharge chutes for the passage of such acceptable coins and a common reject chute for the non-acceptable coins, coin-testing means including a plurality of coin-engaging elements in said passage

for deflecting and directing the introduced coins to their respective acceptance or non-acceptance discharge chutes, superposed runways in the coin passage between the coin-receiving opening and said testing means for guiding twenty-five cent coins to a predetermined area of the testing means and the five and ten-cent coins jointly to another predetermined area of the testing means, certain of said coin-engaging elements being in that testing area in the path of trajectory of the 25¢ coin guiding runway and between which acceptable 25¢ coins pass to their discharge chute and from which elements unacceptable coins are directed for passage to the reject chute, and the remaining coin-engaging elements being disposed in that testing area in the path of trajectory of the 5¢ and 10¢ runway and between one or another of which acceptable 5¢ and 10¢ coins pass to their respective discharge chutes and from one or another of which last-named coin-engaging elements unacceptable coins are deflected for passage to the reject chute and means along each of said runways for creating a magnetic field to vary the trajectory path of the coins, whereby coins of acceptable characteristics are directed by the testing means to the companion denominational acceptance discharge chutes while coins of non-acceptable characteristics are directed by said testing means to the common reject chute.

4. A coin device of the character described, comprising means defining a coin passage having a common coin-receiving opening for the introduction of a plurality of coins of different denominations and separate discharge chutes for acceptable and non-acceptable coins, certain of the acceptable chutes and the non-acceptable chute being disposed side by side in the lower portion and plane of the coin passage and another of the acceptable chutes being disposed at the opposite side of said coin-passage-means, the latter having a laterally-disposed opening and deflector communicating with the last-named chute and into which acceptable coins of a given denomination are directed, means disposed in cooperative relation with said opening and deflector for directing non-acceptable coins of said last-named denomination clear of the companion acceptable chute and downwardly into the coin passage, spaced deflector elements projecting into the coin passage between said lower discharge chutes and said opening and deflector and between which certain of the coins are adapted to pass or be deflected into companion acceptance chutes in the lower portion of the coin passage or to be deflected into the non-acceptance discharge chute, and means providing a magnetic field across the coin passage between its coin-receiving opening and said laterally-disposed opening and deflector elements.

5. A coin device of the character described, comprising means defining a coin passage having a common coin-receiving opening at its upper end for coins of different denominations and a pair of acceptance chutes in its lower portion for the separate discharge of genuine coins of certain denominations and a common reject chute for spurious coins of the different denominations, said means having an auxiliary acceptance chute at the rear side of said coin passage and in communication with the upper portion of the latter for receiving genuine coins of another denomination, means in the upper portion of the coin passage for dividing the same into superposed runways whereby the coins of the last-recited denom-

ination are guided in a direction toward said auxiliary acceptance chute while coins of said certain denominations are guided in a direction below the entrance to such chute, means for providing a magnetic field across the respective runways in the coin passage, and a plurality of spaced deflectors projecting into said coin passage for intercepting and deflecting the coins as they leave said runways in different trajectories to either the acceptance or reject chutes in the lower portion of said means, two of said deflectors being positioned in superposed relation adjacent the opposite ends of the entrance to said auxiliary acceptance chute, the third deflector being disposed below the lower runway and laterally spaced from the lower deflector of said pair to provide a space between which the different denomination coins may descend, and the fourth deflector being disposed in spaced relation below and substantially midway between said last-named spaced deflectors and from which the descending coins are deflected into one of said lower acceptance chutes or into the reject chute.

6. A coin device of the character described, comprising means defining a coin passage having a common coin-receiving opening at its upper end for coins of different denominations and a pair of acceptance chutes in its lower portion for the separate discharge of genuine coins of certain denominations and a common reject chute for spurious coins of the different denominations, said means having an auxiliary acceptance chute at the rear side of said coin passage and in communication with the upper portion of the latter for receiving genuine coins of another denomination, means in the upper portion of the coin passage for dividing the same into superposed runways whereby the coins of the last-recited denomination are guided in a direction toward said auxiliary acceptance chute while coins of said certain denominations are guided in a direction below the entrance to such chute, means for providing a magnetic field across the respective runways in the coin passage, a plurality of spaced deflectors projecting into said coin passage between said magnetic field creating means and said lower acceptance and reject chutes for intercepting and deflecting the coins as they leave the runways in different trajectories to the reject chute or one of the lower acceptance chutes, and an anvil disposed in the lower portion of the coin passage in adjoining relation to the reject chute and from which genuine coins of a certain denomination are adapted to engage and be rebounded into the other of said lower acceptance chutes.

7. A coin device of the character described, comprising means defining a coin passage having a common coin-receiving opening at its upper end for coins of different denominations and chutes at the lower end for the separate discharge of acceptable coins and a reject chute for the common discharge of non-acceptable coins, means disposed in the coin passage between said coin-receiving opening and said chutes for testing the coins and directing them accordingly to the respective acceptance or reject chutes, and a receptacle applied to the lower portion of said means with its rear wall in spaced overlying relation to its coin passage to form a continuation of the latter and having an opening in such rear wall and in register with the upper portion of the reject chute for receiving certain unacceptable coins said receptacle being open at its upper end in communicating relation with the upper por-

tion of the coin passage for receiving other unacceptable coins.

8. A coin device of the character described, comprising an upright plate, a horizontally-movable gate hinged to said plate at the front side thereof and jointly forming therewith a coin passage, a spring connected to said gate for yieldingly resisting its movement out of its normally closed position, means in the coin passage for checking the descent of unacceptable coins therethrough, said plate having openings therein opposite said coin-checking means, a horizontally-movable knockout member hinged to the opposite side of said plate and having coin-engaging elements thereon in registration with said plate-openings, and an operative connection between said gate and said knockout member for compelling their simultaneous movement toward and from, and vice versa, the opposite sides of said plate, respectively, whereby when said gate is opened to a coin-scavenging position, the knockout member is moved toward said plate to project its coin-engaging elements through the companion plate-openings to release any checked coins lodged in the coin passage.

9. A coin device of the character described, comprising an upright plate, a horizontally-movable gate hinged to said plate at the front side thereof and jointly forming therewith a coin passage, a spring connected to said gate for yieldingly resisting its movement out of its normally closed position, means in the coin passage for checking the descent of unacceptable coins therethrough, said plate having openings therein opposite said coin-checking means, a horizontally-movable knockout member hinged to the opposite side of said plate and having coin-engaging elements thereon in registration with said plate-openings, an abutting connection between said gate and said knockout member for maintaining such parts in predetermined relation, a spring connected to the gate and knockout member for normally urging said parts toward each other at all times, and an actuating member mounted on said plate for operative engagement with said gate to move it to an open position, said last-named spring simultaneously causing the movement of the knockout member in a like direction to project its coin-engaging elements through the companion plate-openings to release any checked coins lodged in the coin passage.

10. A coin device of the character described, comprising an upright plate, a horizontally-movable gate hinged to said plate at the front side thereof and jointly forming therewith a coin passage, a spring connected to said gate for yieldingly resisting its movement out of its normally closed position, means in the coin passage for checking the descent of unacceptable coins therethrough, said plate having openings therein opposite said coin-checking means, a horizontally-movable knockout member hinged to the opposite side of said plate and having coin-engaging elements thereon in registration with said plate-openings, a magnet mounted on said gate and an opposing keeper element mounted on said knockout member for creating a magnetic field across the coin passage and adapted to arrest magnetic coins therebetween, means operatively connecting said gate and said knockout member for joint movement whereby, when the gate is opened to a scavenging position, the knockout member is moved toward said plate to project its coin-engaging elements through the companion plate-openings to release any checked coins lodged in

5 the coin passage, a sweep arm pivotally mounted on the inner side of the gate and movable across the space between the magnet and its keeper for removing any coin arrested thereby, and an actuating member operatively connected to said gate and said sweep arm for controlling the movement of such parts and the knockout member to their scavenging positions.

11. A coin device of the character described, 10 comprising an upright plate, a horizontally-movable gate hinged to the upper portion of said plate at the front side thereof and jointly forming therewith a coin passage, a horizontally-movable scavenger member hinged to the opposite side of said plate and having deflector elements thereon projectable through companion openings in the plate and across the coin passage, a receptacle for unacceptable coins mounted on the lower front side of said plate in spaced relation thereto to form a continuance of the coin passage, means in the coin passage for arresting magnetized and other unacceptable coins introduced thereto, means movably mounted on said gate for releasing any magnetized coins from the coin passage, and an actuating means operatively connected to said gate, said scavenger member and said coin releasing means for controlling the movement of such parts to their scavenging positions, the deflector elements on said scavenger member causing the released coins to be deflected into said receptacle.

12. A coin device of the character described, 15 comprising an upright plate, a horizontally-movable gate hinged to the upper portion of said plate at the front side thereof and jointly forming therewith a coin passage, a horizontally-movable scavenger member hinged to the opposite side of said plate and having elements thereon projectable through companion openings in the plate and across the coin passage to release any coins, arrested in such passage, a receptacle for unacceptable coins mounted on the lower front side of said plate in spaced relation thereto to form a continuance of the coin passage, the inner wall of said receptacle having an opening therein and a movable door normally closing the same, and means for actuating said scavenger member to its operative position to release arrested coins, one of said elements on the scavenger member being positioned opposite said receptacle door to open the same while another of said elements is adapted to release and direct any coin arrested in the region of the receptacle-door through the same and into the receptacle.

13. A coin device of the character described, 20 comprising means defining a coin passage having a common coin-receiving portion at its upper end and chutes for the separate discharge of acceptable and non-acceptable coins, a horizontally-swinging gate mounted on said means and jointly forming therewith the coin passage and having an opening therein in register with the coin-receiving portion thereof for the discharge of undersize coins, and a counter-balanced lever pivotally mounted on said means and having a forwardly-bent portion at its lower end normally extending transversely of the coin-receiving portion of the coin passage, said lever being displaceable by coins of normal weight and size to permit them to descend into the coin passage while coins of undersize are projected by said lever through said gate-opening.

14. A coin device of the character described, 25 comprising an upright plate, a horizontally-movable gate hinged to said plate in overlying rela-

tion thereto and jointly forming a coin passage therewith, a horizontally-movable knockout member hinged to the opposite side of said plate and operatively connected to said gate to move simultaneously therewith relative to said plate, the latter having an opening therein in the plane of the gate and the knockout member, and a magnet and a companion keeper applied to said gate and said knockout member, respectively, in registering relation with the plate-opening, the keeper normally extending through said opening flush with the upright plate and adapted to protrude through said opening in constant predetermined relation with the magnet when said gate and knockout member are jointly moved from a normal position to an abnormal position.

15. A coin device of the character described, comprising means defining a coin passage having a common coin-receiving opening at its upper end for the introduction of 5¢, 10¢ and 25¢ coins and separate discharge chutes at its lower end for the passage of acceptable coins of such denominations and a reject chute for non-acceptable coins, a pair of coin-separating runways leading from the coin-receiving opening and disposed one below the other with the upper runway accommodating 25¢ coins and the lower runway 5¢ and 10¢ coins, means in said coin passage for intercepting and directing 25¢ coins to the upper runway and permitting 5¢ and 10¢ coins to drop unimpeded onto the lower runway, means along each of the runways for creating a magnetic field to vary the trajectory path of the coins, and coin-testing means in the coin passage between the ends of the runways and the coin discharge chutes for deflecting and directing the introduced coins to their respective acceptance or non-acceptance discharge chutes, said means consisting of a plurality of spaced pairs of coin-engaging elements disposed in predetermined relation and at predetermined trajectory distances from the ends of said runways and between which companion ac-

ceptable coins are free to pass for direction to the respective acceptance discharge chutes, any coins contacting said elements by trajectory in an abnormal path being deflected out of the acceptance chute-paths and into the discharge chute.

16. A coin device of the character described, comprising means defining a coin passage having a common coin-receiving opening at its upper end for the introduction of 5¢, 10¢ and 25¢ coins and separate discharge chutes at its lower end for the passage of acceptable coins of such denominations and a reject chute for non-acceptable coins, a pair of coin-separating runways leading from the coin-receiving opening and disposed one below the other with the upper runway accommodating 25¢ coins and the lower runway 5¢ and 10¢ coins, means in said coin passage for intercepting and directing 25¢ coins to the upper runway and permitting 5¢ and 10¢ coins to drop unimpeded onto the lower runway, means along each of the runways for creating a magnetic field to vary the trajectory path of the coins, coin-testing means in the coin passage between the ends of the runways and the coin discharge chutes for deflecting and directing the introduced coins to their respective acceptance or non-acceptance discharge chutes, said means consisting of a plurality of spaced pairs of coin-engaging elements disposed in predetermined relation and at predetermined trajectory distances from the ends of said runways and between which companion acceptable coins are free to pass for direction to the respective acceptance discharge chutes, any coins contacting said elements by trajectory in an abnormal path being deflected out of the acceptance chute-paths and into the discharge chute, and an anvil disposed in the reject chute and from which acceptable 5¢ coins are adapted to rebound and be trajectory between a pair of said coin-engaging elements into the companion acceptance discharge chute.
